DESIGN FOR A SHOE OR SIMILAR ARTICLE

Lorenzo Audino, East Elmhurst, N. Y.

Application April 10, 1935, Serial No. 56,305

Term of patent 3½ years

To all whom it may concern:

Be it known that I, Lorenzo Audino, a citizen of the United States, residing in East Elmhurst, in the county of Queens and State of New York, have invented a new, original, and ornamental Design for a Shoe or Similar Article, of which the following is a specification, reference being had to the accompanying drawing, forming part thereof.

Figure 1 is a plan view of a shoe, showing my new design.

Figure 2 is a side perspective view of the shoe.

The dominant feature of the present design resides in the ornamental effect produced by the vamp having contrasting materials in the lower and upper portions thereof, the lower or toe portion having an integral strip extending upwardly to the instep of the shoe of the same material as the toe portion.

I claim:

The ornamental design for a shoe or similar article, as shown and described.

LORENZO AUDINO.
